UNITED STATES PATENT OFFICE.

SVEN P. ALQUIST, OF SEDALIA, MISSOURI, AND ALLAN S. BARROWS, OF CHICAGO, ILLINOIS, ASSIGNEES OF ONE-THIRD TO W. L. KELLOGG, OF DETROIT, MICHIGAN.

FREIGHT-CAR CONSTRUCTION.

1,379,952.

Specification of Letters Patent.

Patented May 31, 1921.

Application filed December 14, 1916. Serial No. 136,846.

To all whom it may concern:

Be it known that we, SVEN P. ALQUIST, of Sedalia, Pettis county, Missouri, and ALLAN S. BARROWS, of Chicago, Cook county, Illinois, both citizens of the United States, have invented a certain new and useful Improvement in Freight-Car Constructions, of which the following is a full, clear, concise, and exact description, reference being had to the accompanying drawings, forming a part of this specification.

This invention relates to improvements in freight car construction, and more particularly to an improved arrangement of inside doors adapted to both protect the outside door from shifting loads and to serve as a grain door.

Other and more specific objects of the invention are to provide an arrangement of the character above indicated so designed that the threshold and the door posts of the car are strengthened and reinforced by means of plates which are also arranged to coöperate and function with the inside door; to provide simple, automatically operated means for locking the inside door in its different positions; and to provide simple means for opening the inside door by using a pinch bar or other similar suitable tool.

The invention furthermore consists in improvements in the parts and devices and in the novel combination of the parts and devices herein shown, described or claimed.

In the drawing forming a part of this specification, Figure 1 is a side elevation of a portion of a freight car showing our improvements in connection therewith. Fig. 2 is a horizontal sectional view taken on the line 2—2 of Fig. 1. Fig. 3 is a vertical section taken substantially on the line 3—3 of Fig. 1. Fig. 4 is an inside elevation of the car, the full lines illustrating the position of the inside door in closed position, and the dotted lines the position of the door when open or in inoperative position. Fig. 5 is a detailed view, upon a larger scale, illustrating more particularly the latch for locking the door in its different positions. Figs. 6 and 7 are detailed sectional views taken on the lines 6—6 and 7—7 respectively of Fig. 5. And Fig. 8 is an enlarged horizontal sectional view taken substantially on the line 8—8 of Fig. 1.

Referring to said drawing, 10 denotes the side wall of the car having the usual door

opening 11 therein, 12—12 the side posts of the door opening and 13 the threshold, the same being cut out or rabbeted as clearly indicated in Figs. 1, 2 and 3 at 14 to accommodate a flush outer door (not shown). The improved inside door is indicated at 15 and, as shown, comprises a steel plate preferably of $\frac{1}{8}$ " thickness, the same being dished inwardly as indicated at 16 in Fig. 3. In order to increase the strength of the door and better adapt it to resist the pressure from the loading thereagainst, the dished portion of the same is provided with a series of preferably longitudinally extending corrugations 17—17. In order to adapt the door 15 for grain service, said door is provided with a smaller hinged relief door 18 near the right-hand lower corner thereof, as clearly indicated in Fig. 1. The relief door is held closed by any suitable means, such as the turn button 19, it being understood that the corrugations and relief door with its lock are disposed within the plane of the rim portions of the door 15.

The door 15 is slidably mounted between a pair of plates 20 and 21, the former being mounted on the floor of the car and extending over the threshold as indicated at 22 to thereby reinforce the latter and minimize wear due to trucks, etc. The plate 20 is provided with a longitudinally extending central groove 23 in which the lower edge of the door 15 slides. The upper plate 21 is bolted or otherwise suitably secured to the inner wall of the car and is provided with an inwardly extending, turned over edge 24 to thereby form a longitudinally extending groove or guide for the upper edge of the door. The plate 20, as shown, is provided with upward extensions 25 and 26 at the opposite sides of the door opening, said extensions being secured to the inner faces of the door posts 12 to thereby strengthen the latter and prevent excessive wear thereof. The portions 25 and 26 are shown as extending only a relatively short distance up the post 12, but as will be understood by those skilled in the art, these portions may be made of any desired length to suit varying conditions. The left-hand post 12, as viewed in Figs. 1 and 2, is provided on the inner side thereof with a vertically extending plate 28 which not only protects the post from the use of nails and strengthens it, but has formed thereon a flange 29 to thereby

provide a vertical groove within which is received the advance doubled over edge 30 of the door 15 to form a grain seal when the door 15 is in closed position. Said plate 28 is also provided with a horizontal extension at the top as indicated at 27 to fit over the top of the door 16 when in closed position and prevent it from being displaced vertically. The right hand door post 12 is provided on its inner face with a plate 40 having a bent flange 41 to form a vertical groove in which seats the hooked shaped vertical rear edge 42 of the door 16 to form a grain seal.

In order to retain the door 15 in either closed or open position, we have provided a pivoted latch or lock 31 mounted in a bracket 32 counter-sunk into one of the posts 12, as clearly indicated in Figs. 4, 5, 6 and 7. The upper edge of the door 15 is provided with two notches 33 and 34, the former near the advance edge of the door and the latter near the rear edge so that, when the door is in closed position, the gravity latch 31 will drop into the notch 34 and hold the door closed and when the door is in open position, said latch will fall into the notch 33 and hold it in said position. The bracket 32 is provided with a tapered socket 33 which will permit the latch 31 to swing upwardly to thereby clear the door, as is apparent from Fig. 7. To open the door 15 when there is any pressure thereon from the interior of the car, the latch 34 is, of course, first lifted and then a pinch bar or other suitable tool is inserted between the shoulder 34' on the door 15 and the adjacent portion 25 of the reinforcing plate 22. As clearly appears from Figs. 2 and 8, the shoulder 34', which may be in the form of a short section of angle iron riveted or otherwise secured to the door, is so located as to provide sufficient clearance 35 to permit the insertion of the tool for prying the door open. The shoulder member 34', being applied to the counter-sunk or dished portions of the door 15, will clear the right-hand post 12, as viewed in Fig. 2, when the door 15 is open.

From the preceding description, it will be seen that the arrangement which we have provided is well adapted for the purpose of protecting the outside door from shifting loads in the car and consequent damage thereto, since the door 15, being dished inwardly and corrugated, is exceedingly strong for its weight and is thereby also

well designed for use as a grain door. When used as a grain door, a grain seal is formed along the bottom and both vertical edges thereof. Furthermore, by means of our improved inside door, the lading is protected from theft inasmuch as it is practically impossible to get at the lading to remove the same while the outside door is closed even though the outside door is opened at the end opposite to the seal. The plates on the threshold and door posts not only strengthen the car structure, but prevent the driving of nails into the wooden members and thus eliminate another frequent cause of damage to the car.

Although we have herein shown and described what we now consider the preferred embodiment of our invention, the same is merely illustrative and we contemplate all changes and modifications that come within the scope of the claim appended hereto.

We claim:

In a car having a door opening in a side wall thereof, defined by side posts, threshold and lintel, the combination with a door horizontally slidably mounted on the inner side of said wall, of fixed means, disposed outside of the door opening arranged to thereby leave the latter unobstructed, co-operable with the side and bottom edges of the door to form a grain seal therewith when the door is in closed position, said door being formed of sheet metal and having a central, corrugated inwardly dished portion and flat marginal portions, the latter adapted to slidably bear against the inner face of said side wall, said door having an auxiliary relief door disposed within the area of the dished portion and inwardly of the plane defined by said flat marginal portions to thereby avoid interference when the door is moved to one side of the door opening back of the side wall of the car.

In witness that I claim the foregoing, I have hereunto subscribed my name this 16th day of November, 1916.

SVEN P. ALQUIST.
